A. O. Crane Inventor.

United States Patent Office.

ALBERT O. CRANE, OF BOSTON, MASSACHUSETTS.

Letters Patent No. 113,266, dated April 4, 1871; antedated March 24, 1871.

IMPROVEMENT IN STOOLS OR TABLES.

The Schedule referred to in these Letters Patent and making part of the same.

I, ALBERT O. CRANE, of Boston, in the county of Suffolk and State of Massachusetts, have invented certain Improvements in the Construction of Stools and Tables with Folding-supports, of which the following is a specification.

Nature and Objects of the Invention.

My invention belongs to that class of stools or tables, and other like articles, so constructed that the seat and supports can be folded together into a flat and compact mass or shook, for convenient transportation and storage.

Description of the Accompanying Drawing.

The drawing represents the different parts of a stool, but the same mode of construction may be employed in making a chair, table, or other like article.

Figure 1 represents an oblique side view of the stool as adjusted for use.

Figure 2 represents the whole folded, with the seat down.

Figure 3 represents the whole folded, with the seat uppermost.

Figure 4 represents a front view of the whole with the seat down and the supports spread out their full length.

Figure 5 represents a side view of the same with the seat uppermost.

The same letters represent the same parts in each figure.

General Description.

A is a seat or platform, which should be made substantially, that it may support the weight for which it is intended, and afford adequate rest for the hinges upon which the supports swing.

To give strength to this I fix firmly on the underside a cleat or block, a, upon which and on the underside the hinges b b for the supports are screwed. These hinges may be fastened directly upon the seat A, and the cleat a omitted; but I prefer to employ the cleat, and find it adds greatly to the strength and durability of the article when placed so that the grain (if of wood) runs at right angles to the grain of the seat.

The supports B and C, each to swing on one of the hinges b b, and each terminating in two legs or feet, are so constructed that they may cross each other about midway of their length, and, at the crossing, one may match into the other with all their respective appliances.

The two legs c c of support B are so far asunder as to permit support C to pass between them in the act of folding or opening.

The space between the legs, as it approaches a point midway of the length of B, assumes the form of a slot, d, with parallel sides, the upper part or top of which is in a line at right angles with the sides, but so beveled in the thickness of the wood that the slot d is longer on the inside than on the outside of the support. This bevel should be at such an angle that support C will, when adjusted for use, bear evenly upon all parts of the thickness of the wood of B at this point.

For greater strength and support I place across B, at a point coinciding with the said beveled top of said slot d, a cleat, e, also beveled in the same plane or angle. When adjusted for use, support C will bear directly and evenly upon said top of the slot d and the beveled or lower side of the cleat e. The cleat e serves the further purpose of strengthening the support B at its weakest point.

Support C terminates, like B, in two legs, f f, which branch from the body of C at a point about three-fourths the length from the upper end.

About the middle of C two shoulders, g g, are formed, in and at right angles to the sides, by cutting the sides down, so as to form from or in the body of C the bar h, of a width to fit the slot d in B. These shoulders are beveled at such an angle, and are at such a point in C that, when the supports are adjusted for use, the top of the slot d in B will bear evenly upon the whole thickness of the wood of C.

The section of support C above designated as the bar h, extends from said shoulders g g on the outside a distance equal to the thickness of support B and the lock-bar, hereinafter described.

On the outside of the bar h, and at a point about one inch from the lower line of intersection of supports B and C, when adjusted for use, I place a cleat, i, the upper side of which is beveled at the same angle with the shoulders g g. This cleat i may be extended downward, so as to give greater strength to C, especially at the point of bifurcation of the legs f f.

On one of the legs of support B I swing a lock-bar, j, of length sufficient to extend across and lock upon the other leg, and of such thickness as to fit firmly upon the top of cleat i. This lock-bar has its upper edge beveled at the same angle as the top of the slot d and the bottom of the cleat e, and is swung on the leg of B at a point as far below the said bottom of cleat e as the thickness of support C at the bar h.

On the other leg of support B I fix a catch or button, k, or some other device, for holding the lock-bar j in place.

Mode of Operation.

When the supports B and C are fixed upon the

seat or the cleat *a* by means of the hinges *b b*, the lower extremities are brought together, and *C* is pressed down between the feet of *B* until the bar *h* is brought to bear against the top of the slot *d* and the bottom of the cleat *e*, and, at the same time, those parts of support *B* which form the sides of the slot *d* will bear upon the shoulders *g g* in support *C*; the lock-bar *j* is then swung upon its pivot, and its beveled edge brought to bear upon the outer side of bar *h* in support *C*, and its outer side brought over and against the beveled edge of cleat *i*, when it is held in place by turning the button *k*, or other device. The two supports are thus locked in position and form a firm and substantial rest for the seat *A*. Swing the lock-bar *j* from the above position, separate the supports *B* and *C*, fold *B* back in a line with the cleat *a* or the under side of the seat *A*, and fold *C* down upon it, and the whole is in compact form for transportation or storing.

When folded, any mode of fastening its parts to-

gether may be adopted. I fix a headed catch in support *B*, which passes through a slot in *C*, and, being turned, fastens the parts together securely. I have also arranged a handle for carrying the stool; but for both these purposes many other devices equally good may be substituted.

Claim.

I claim as my invention—

A platform, *A*, resting upon hinged supports *B* and *C*, operating and locking together by means of the bar *h*, slot *d*, the shoulders *g g*, lock-bar *j*, cleats *e* and *i*, and the button *k*, constructed and operating substantially as and for the purposes hereinbefore set forth.
